UNITED STATES PATENT OFFICE.

ALFRED H. GREBE, OF RICHMOND HILL, NEW YORK, ASSIGNOR TO A. H. GREBE & CO., INC., OF RICHMOND HILL, NEW YORK, A CORPORATION OF NEW YORK.

DESIGN FOR A CONTROL-HANDLE FOR REGULATING APPARATUS.

57,900.

Specification for Design.

Patented May 17, 1921.

Application filed May 12, 1920. Serial No. 380,924. Term of patent 7 years.

To all whom it may concern:

Be it known that I, ALFRED H. GREBE, a citizen of the United States, residing at Richmond Hill, in the county of Queens and State of New York, have invented a new, original, and ornamental Design for a Control-Handle for Regulating Apparatus, of which the following is a specification, reference being had to the accompanying drawing, forming part thereof.

Figure 1 is a front elevation, Fig. 2 is a

side elevation, and Fig. 3 is a view in perspective of a control handle for regulating apparatus showing my new design.

I claim:

The ornamental design for a control handle for regulating apparatus as shown.

ALFRED H. GREBE.
